UNITED STATES PATENT OFFICE.

MORRIS F. BRAINARD, OF BROOKLYN, NEW YORK.

PUMP-EXCAVATOR.

SPECIFICATION forming part of Letters Patent No. 363,202, dated May 17, 1887.

Application filed January 22, 1886. Serial No. 190,121. (No modcl.)

To all whom it may concern:

Be it known that I, MORRIS F. BRAINARD, a citizen of the United States, and a resident of Brooklyn, in the county of Kings and State of New York, have invented certain new and useful Improvements in Pump-Excavators, of which the following is a specification.

My invention relates to that class of excavators where the material is elevated from the bottom by means of a pump and deposited in a scow.

The object of my invention is to construct a self-loading scow or barge having the machinery and all the appliances placed thereon, and so arranged as to secure the best results by reducing the height of the lift and to retain the material in the scow securely and to discharge it freely when desired, which will be hereinafter more fully explained, reference being had to the accompanying drawings, in which—

Figure 1 represents a longitudinal section of the stern of the scow or barge. Fig. 2 represents plan of same. Fig. 3 is a side elevation 25 of the pockets and valves in section and enlarged. Fig. 4 shows a cross section of Fig. 3. Fig. 5 is a plan of one of the valves detached. Fig. 6 shows a section of flexible suction hose enlarged. Fig. 7 represents a clamping device for securing suction-pipe in section enlarged. Fig. 8 is an end view of same in section on line x-x of Fig. 7. Fig. 9 is a modification of the valve-doors.

A represents the scow or barge, in the stern 35 of which is constructed a well or open-end tank, B, the sides and end 1 2 3 of which are water-tight. The deck 4 of the well is placed a little above light water line C. On the deck 4 in the well B is placed the pump D and universal joint E, (which is described in Letters Patent of the United States, No. 332,228, granted to me on the 15th day of December, 1885,) to which the suction-pipe F is attached, and thence extending over aft to the bottom. 45 The well B may be cut out entirely, if desired, and the pump D set on cross-timbers.

The driving-shaft 5 of the pump passes through the wall 2, and is kept tight by a suitable stuffing-box, 6, the shaft being there attached to the driving-power, placed in the compartment G surrounding the well or tank B. One or more pumps may be placed in the well

B, if desired. Connecting the pump D and the suction-pipe F, inside of the universal joint E, is a section of flexible suction-hose, H, consisting of one or more conical thimbles, 7, which overlap one another freely, and the whole is covered with a flexible corrugated covering, S, as shown in Fig. 6, which allows the section of hose H to be twisted and bent in any direction 55 desired freely. The said thimbles 7 are prevented from being displaced endwise by the inward-protruding lugs 9 on thimbles 10 and pins 11, or any other suitable holding device may be employed. The thimbles 7 may be removed when clean water is being pumped, as the said thimbles 7 are only used to prevent the inner corrugation from wearing off.

To facilitate the removing of the thimbles 7 when desired, one of the thimbles, 10, is made 70 larger than the large end of said thimble 7, so that the said thimble will pass through freely, and they are prevented from going in the opposite direction by the inward-protruding lug 9.

Attached to the suction-pipe F, just outside 75 of the universal joint E, is a bell-mouth connecting-joint, K, which consists of the conical sleeve 12, sitting on the cone-sleeve 13, both of which are connected together by the hinge 14, and the said sleeves 12 and 13 are securely 80 clamped together when working by the lugs 15, which are secured to sleeve 12, and passing through flange 17 of sleeve 13, where they are caught by the bevel or wedges a on ring 16, placed back of the flange 17 and operated by 85 the bevel-pinion 18 and handle 19, the said ring 16 locking or clamping all the lugs simultaneously. The handle 19 extends above the deck of the scow or barge, so that the joint K can be connected or disconnected when submerged to the water-line L. The object of submerging the whole appliance is to prevent any air-leaks that may occur, and also to lessen the height of the lift of the material from the bottom.

To the lower end of the suction-pipe F is attached the oscillating suction-shoe N, to the after end of which is secured a roller, 25, to prevent the shoe N catching in the material and breaking the pipe F or its connections if the boat should be moved backward.

The material is discharged into the pockets M by the discharge-pipe 20. The bottoms of the pockets M are provided with valves 21,

which are beveled to fit from below in corresponding seats, 22, and held in place by screws 23; but any other suitable holding device may be used. The valves 21 being fitted as shown, prevent any of the material from leaking out, but are readily opened by lowering same when it is desired to discharge the load. The valves 21 may be made square, if desired, and hinged at one side, as shown in Fig. 9, and hang down from one side, as shown by dotted lines, and to enable the said valve to be seated securely the hinge 26 is made with an oblong hole, which will overcome any wear there may be in seat 22.

What I claim, and desire to secure by Letters Patent, is—

1. In an excavating scow or barge, A, the well or tank B, placed in the stern thereof, the deck thereof being just above the light water line, substantially as and for the purpose specified.

2. In an excavating scow or barge, the flexible suction-hose consisting of one or more conical thimbles, 7, securely held in place by lugs 9 and pin 11, and the corrugated flexible covering 8, substantially as and for the purpose specified.

3. In an excavating scow or barge, the bell-mouth connecting-joint K, hinged together at 14, and one part thereof provided with lugs 15, which engage with bevels or wedges α , attached to the ring 16 and operated by pinion 18, substantially as and for the purpose specified.

Signed at New York, in the county of New York and State of New York, this 26th day of January, A. D. 1886.

MORRIS F. BRAINARD.
